UNITED STATES PATENT OFFICE.

JOHN A. CHAMBERS, OF NEWBURG, MISSOURI, ASSIGNOR OF ONE-FOURTH TO JOHN A. POTTER AND ONE-FOURTH TO HENRY F. WARNEKE, SR., BOTH OF ST. LOUIS, MISSOURI, AND ONE-FOURTH TO HENRY F. WARNEKE, JR., OF MAPLEWOOD, MISSOURI.

DOOR-OPERATING MECHANISM.

1,821,887.

Specification of Letters Patent. Patented Nov. 18, 1919.

Application filed March 6, 1919. Serial No. 281,044.

To all whom it may concern:

Be it known that I, JOHN A. CHAMBERS, a citizen of the United States, residing at Newburg, in the county of Phelps and State 5 of Missouri, have invented a new and useful Door-Operating Mechanism, of which the following is a specification.

This invention relates to door operating mechanism and its principal object is to 10 provide a mechanism of this character which will open and close a heavy door such as a refrigerator door with great facility.

A second object of the invention is to provide a door opening and closing mechanism 15 which may be applied to any door construction without materially altering the same and which may be readily placed in operative position.

A further object of the invention is to 20 provide a door operating mechanism which is easily and quickly operated.

A still further object of the invention resides in the provision of a door operating mechanism which is neat in appearance and 25 which does not possess any cumbersome parts which are likely to become broken.

Another object of the invention is to provide a door operating mechanism which is simple in construction, consists of few parts 30 which may be readily assembled and disassembled, and which may be manufactured and installed at a minimum cost.

Other objects and advantages will become 35 apparent from the following specification and accompanying drawing.

The invention consists of constructions, combinations, arrangements, and general assemblage which will be specifically referred to and illustrated in the accompanying 40 drawing wherein:—

Figure 1 is a front elevation of a refrigerator having my door operating mechanism applied thereto.

Fig. 2 is a top elevation of the same, and 45 Fig. 3 is a vertical sectional view through the refrigerator and showing parts of the mechanism in section.

Referring in detail to the drawing wherein like characters of reference indicate like 50 parts the numeral 5 designates a swinging refrigerator door of usual construction hinged to the wall 6 of the refrigerator.

Extending vertically from the door 5 is a post 7 to which is attached a flexible element 8 that extends through a pulley 9 on 55 the bracket 10 which is secured to the wall 6 of the refrigerator. This flexible element 8 runs along the top of the refrigerator and thence downwardly and through a pulley 11 to a point where it may be grasped by 60 the operator. By pulling on this flexible element the door 5 is swung to a closed position.

One end of a lever 12 is pivotally mounted in a bracket 13 positioned on the wall 6. A 65 stop 14 projects from the wall 6 to limit the downward movement of the lever. The flexible element 8 is attached to the end of the lever and extends between the sheaves 11 and thence to a position where it may 70 be grasped by the operator.

Mounted on the wall 6 above the door 5 is an inverted V shaped bracket 17. Braces 18 extending from the wall 6 are positioned upon either side of the bracket 17 and are 75 connected thereto.

Pivots mounted in the bracket 17 is a door opening member 18' of eccentric formation. This eccentric shaped member is adapted to engage a vertically extending 80 post 19 mounted at the forward end of the door. The inner face of the post 19 is inclined. Links or other flexible elements are suspended from the lever 12 and are connected with the member 18. 85

The operation of my improved door operating mechanism is as follows:

The door being in closed position the operator pulls the flexible element 8 which causes the eccentric member 18' to be swung outwardly where it engages the post 19 and forces the door open. When it is desired to close the door, it is only necessary to pull the flexible element 8 and the door will be drawn to closed position. 90

This embodiment of the invention is considered to be preferred construction but I wish to here state that the invention may be modified in many different respects and that my limits of modification are only governed 100 by the herewith appended claims.

What is claimed is:

1. In a door operating mechanism, the combination with a swinging door, of a post

secured to the door and projecting beyond one edge of the same and having its inner face inclined, an eccentric shaped member pivoted adjacent the door and movable at right-angles to the inclined face of the post and movable thereover, a lever pivotally connected with the eccentric shaped member, and means for moving the lever thereby to rock the eccentric shaped member to move the same over and against the post to open the door.

2. In a door operating mechanism, a swinging door, an inverted V shaped bracket mounted above the door, an eccentric shaped member pivotally mounted in the bracket, a post carried by the door adapted to be engaged by the eccentric shaped member to move the door to an open position, a lever mounted above the door and operatively connected with the eccentric member, a flexible element for operating the lever, and means for closing the door.

3. In door operating mechanism a swinging door, a vertical post carried by the door

and projecting above the upper edge of the same and having its inner face inclined, a bracket of inverted V-shaped formation, an eccentric shaped member pivoted to the bracket and engageable with the inclined face of the post and having its inner end laterally bent upwardly, a lever pivoted adjacent the eccentric shaped member having operative connection with the upturned end of the eccentric shaped member, and a flexible element having one end secured to the free end of the lever where upon pulling the same the lever will be rocked to rock the eccentric shaped member into engagement with the inclined face of the post to open the door.

In testimony that I claim the foregoing as my own, I have hereto affixed my signature in the presence of witnesses.

JOHN A. CHAMBERS.
